UNITED STATES PATENT OFFICE

147,986

DESIGN FOR AN APRON DRESS OR SIMILAR ARTICLE

Jack Nachman, Philadelphia, Pa.

Application April 8, 1947, Serial No. 138,227

Term of patent 14 years

(Cl. D3—26)

To all whom it may concern:

Be it known that I, Jack Nachman, a citizen of the United States, residing at Philadelphia, in the county of Philadelphia and State of Pennsylvania, have invented a certain new, original, and ornamental Design for an Apron Dress or Similar Article, of which the following is a specification, reference being had to the accompanying drawing, forming part thereof.

In the drawing:

Fig. 1 is a front view of an apron dress or similar article showing my new design.

Fig. 2 is a rear view of the apron dress or similar article shown in Fig. 1.

Fig. 3 is an enlarged view of a portion of the neckline trim of the apron dress or similar article shown in Fig. 1.

I claim:

The ornamental design for an apron dress or similar article, substantially as shown,

JACK NACHMAN.
